UNITED STATES PATENT OFFICE.

FRANK W. EDWARDS, OF CHICAGO, ILLINOIS, ASSIGNOR TO THE CHICAGO LUBRICATOR COMPANY, OF CHICAGO, ILLINOIS, A CORPORATION OF ILLINOIS.

LOCOMOTIVE-CAB SQUIRT.

1,155,474.

Specification of Letters Patent.

Patented Oct. 5, 1915.

Application filed September 21, 1914. Serial No. 862,844.

To all whom it may concern:

Be it known that I, FRANK W. EDWARDS, a citizen of the United States, residing at Chicago, in the county of Cook and State of Illinois, have invented a certain new and useful Improvement in Locomotive-Cab Squirts, of which the following is a full, clear, and exact description.

Under a Federal law administered by the Interstate Commerce Commission, it is required that railway locomotives shall be equipped with safe and suitable boilers and appurtenances, and as an outgrowth of this law locomotives are provided with hose for supplying water for washing the cab deck, sprinkling the coal in the tender to lay the dust, and for putting out the fire in the firebox in emergencies requiring its extinguishment.

In accordance with prevalent practice, the hose connection has been made with the locomotive injector, and the water supplied has been under high pressure and dangerously hot, so that the engineer and fireman have been exposed to danger from scalding, and the hose has been uncomfortably hot to handle, and exposed to rapid deterioration and sudden bursting by reason of the heat and pressure of the water.

The object of the present invention is to meet the requirements of the law in a practical and efficient way, and to remove the dangers and disadvantages incident to present practice, and to supply water at a lower temperature and lower but effective pressure, so that the hose may be comfortably handled, and the engine crew shielded from danger.

The invention consists of a locomotive cab squirt, so called, embodying means by which water under high temperature and high pressure may be mixed with cooler water from a separate source of supply, and the high temperature and high pressure reduced, so that the water may be handled safely and without danger to the apparatus or the attendants, as I will now proceed to explain and finally claim.

In the accompanying drawing illustrating the invention, in the several figures of which like parts are similarly designated, Figure 1 is a side elevation, in outline, of the rear end of a railway locomotive showing one form of installation of the apparatus of this invention, portions of the cab being broken

away. Fig. 2 is a vertical section, and Fig. 3 is a partial horizontal section, on a larger scale, illustrating a temperature and pressure reducing device, or reducer, herein so called for brevity's sake.

1 indicates a portion of a railway locomotive boiler; 2 an ordinary boiler check-valve; 3 the water delivery pipe leading from the injector 4 into the boiler through the check-valve; 5 is the steam supply pipe for the injector; 6 and 7 extension rods for operating the injector-valves, and 8 the water supply pipe for the injector, said water supply pipe being designed to be connected in any usual way with a source of supply of cold water for the boiler, such as the water tank on the tender.

At some point under the influence of the injector, and preferably in the water delivery pipe 3, between the injector and the boiler check-valve, is a coupling 9 to which is secured the pipe 10, preferably of smaller diameter than the water delivery pipe, and this pipe 10 is connected with the inlet nipple 11 of a suitable temperature and pressure reducing device 12, herein referred to as the "reducer". The reducer is connected by an elbow 13 and coupling 14 with the water supply pipe 8 next to the feed water hose connection 15 or other device for connecting the boiler with its water supply, and between said device and the injector. A nipple 16 is connected with the reducer, preferably opposite the inlet nipple 11, and this nipple 16 has connected to it a pipe 17 which has applied to it a controlling-valve 18 of any suitable sort, such as an ordinary globe valve or angle valve, and this last mentioned valve has applied to it a length of hose 19 which may be provided with a nozzle 20. The pipe 17 extends up into the cab and is suitably supported therein, and a bracket 21 may also be placed in the cab to support the hose when not in use. Interposed between the reducer 12 and its connection 13, 14 with the water supply is a check-valve 22 normally seated with the pressure coming into the reducer through the pipe 10 when the valve 18 is closed. The reducer also includes a jet 23 having a small longitudinal passage through it, and the jet 24 arranged opposite the jet 23, and in alignment with it and having a flaring mouth adjacent to the flaring discharge end of the jet 23, and these two jets at their

flared ends are separated, preferably by a narrow space.

I have thus described one installation for carrying out my invention, but wish to be understood as not limiting the invention to the details of construction; but the mechanism shown embodies the principle of the invention in an efficient way.

When it is desired to use water for washing the cab deck or for sprinkling the coal in the locomotive tender, or to put out the fire in the fire-box of the locomotive, as when the water supply for the boiler becomes dangerously reduced or other emergencies arise, the valve 18 is opened, and while the injector is operating, a portion of the water of high temperature and high pressure passing from the injector to the boiler is diverted through the pipe 10 into the reducer, and its alined jets thus become a suction device which draws a portion of the cooler water from the pipe 8 into the reducer past the check-valve 22, which automatically opens under these conditions, and while the pressure coming through the pipe 10 is reduced by the restricted opening in the jet 23, the temperature is also lowered by influx of the cooler water through the pipe 8, and the water is admitted to the hose at a pressure sufficient to clean the cab deck, or sprinkle the coal in the tender, or put out the fire in the fire-box, as may be required, and the temperature is also so far reduced that the hose may be handled comfortably, and all liability of the engine crew to injury from escaping steam, or scalding water, or bursting hose is overcome.

When the squirt is not to be used, the valve 18 is closed and the supply thus cut off. It is to be noted, therefore, that the introduction of the mechanism into the injector circuit does not in any way interfere with the operation of the injector for furnishing water to the boiler.

The fact that the injector is used many times when the cab squirt is not used, requires the use of the check or automatic control-valve 22 located between the water chamber of the reducer and the source of supply of cooler water.

As already sufficiently indicated, the high temperature and high pressure water may be taken at any point under the influence of the injector when working, and the cooler water may be derived from any suitable source; but in the interest of economy and the avoidance of the expense incident to the use of additional parts, I prefer to use an installation substantially such as illustrated.

What I claim is:

1. A locomotive cab squirt, having a temperature and pressure reducing device interposed between a source of supply of water at high temperature and high pressure and a source of supply of cooler water and in

communication with both sources, an outlet for said reducing device, and means to control the outflow from said reducing device through said outlet of the mingled waters at reduced temperature and pressure. 70

2. A locomotive cab squirt, having a temperature and pressure reducing device interposed between a source of supply of water at high temperature and high pressure and a source of supply of cooler water, and means to control the discharge of the commingled two bodies of water from said reducing device. 75

3. A locomotive cab squirt, having a reducer interposed between a source of supply of water at high temperature and high pressure and a source of supply of cooler water and communicating with both sources, an outlet extending from said reducer to the place of delivery of the commingled waters, a valve arranged in said outlet at such place for controlling the delivery, and a check-valve interposed between the reducer and the cooler water inlet to the reducer. 80 85

4. A locomotive cab squirt, having a reducer interposed between a source of supply of water at high temperature and high pressure and a source of supply of cooler water and communicating with both sources, an outlet from said reducer, and a controlling-valve located in said outlet to allow the mixing of these waters and thereby cause a reduction of the temperature and pressure of the water delivered by the reducer. 90 95

5. The combination of an injector, a water supply therefor, a water delivery pipe leading from the injector, means to supply steam to the injector, a reducer, separate means to connect said reducer with the water delivery pipe and the water supply, and means to render the reducer operative to deliver water through it at reduced temperature and pressure. 100 105

6. The combination of an injector, a water supply therefor, a water delivery pipe leading from the injector to a water consumer, means to supply steam to the injector, a reducer connected with said water supply at one point and with said water delivery pipe 110 115 at another point, said reducer having an outlet alined with its connection with said water delivery pipe and a reducing jet and an outlet jet alined with one another and with the intersecting connection with the water delivery pipe, and means to render the reducer operative when the injector is working. 120

7. The combination of an injector, a water supply therefor, a water delivery pipe connecting the injector and a water consumer, means to supply steam to the injector, a reducer connected with the injector's water supply and its water delivery pipe, an automatic valve interposed between the water 125 130

supply and said reducer, and means to render said reducer operative when the injector is working.

8. The combination of an injector, a water supply therefor, independent means to deliver water from said injector and to supply steam to it, a reducer connected with the injector's water supply and its water delivering means, an automatic valve interposed 5 between the water supply and said reducer, a delivery means for said reducer, a hose, and a controlling-valve interposed between 10 the hose and the reducer's delivery means.

9. The combination with a steam generator, a water supply therefor, an injector interposed between said generator and water 15

supply and communicating with both, means to take water from the injector at high temperature and pressure and from the water supply at a lower temperature and 20 little or no pressure and mingle them and reduce the high temperature and pressure, and means to discharge the water, when its temperature and pressure are reduced, under its reduced pressure. 25

In testimony whereof I have hereunto set my hand this 19th day of September A. D. 1914.

FRANK W. EDWARDS.
